UNITED STATES PATENT OFFICE

WILLIAM E. ALBERTSON, OF JACKSONVILLE, FLORIDA, ASSIGNOR OF ONE-HALF TO
MAXEY D. MOODY, OF JACKSONVILLE, FLORIDA

OIL AND TEMPERATURE CONTROLLED IGNITION CUT-OUT

Application filed June 5, 1931. Serial No. 542,392.

This invention relates to oil and temperature controlled ignition cut-outs for automotive engines and has for an object to provide a magnetic ignition switch by means of which the ignition circuit will be automatically opened in the event of the oil pressure or level becoming so low, or the temperature of the cooling system becoming so high, as to endanger the bearings, cylinder walls, and other parts of the motor.

10 A further object is to provide a magnetic ignition switch including a pressure and heat gage operated electro-magnet, and a spring-pressed pivoted switch segment which is released by the magnet for instantly opening the ignition circuit upon a predetermined drop in oil pressure, or predetermined rise in temperature, the device being small, compact, inexpensive to manufacture, and being adapted to be located at any convenient place on the motor or vehicle.

15 A further object is to provide a magnetic ignition switch which may be used as the ignition switch on standard equipment, or may be used independently of or in connection with the standard ignition switch, and may be hooked up to control dual ignition including both magneto and distributor and coil ignition apparatus, or may be used alone 20 to control either magneto ignition apparatus or battery and coil ignition apparatus.

25 With the above and other objects in view the invention consists in certain novel details of construction and combinations of parts hereinafter fully described and claimed, it being understood that various modifications may be resorted to within the scope of the appended claims without departing from the spirit or sacrificing any of the advantages of 30 the invention.

In the accompanying drawings forming part of this specification,

Figure 1 is a sectional view taken on the line 1-1 of Fig. 2 and showing the parts in 35 front elevation in full lines in normal position and in dotted lines in operative position to open the ignition circuit,

Fig. 2 is an end elevation of the switch with the cover removed,

Fig. 3 is a rear elevation of the device,

showing the terminals and showing the spring for controlling the push rod,

Fig. 4 is a detail perspective view of the pivoted armature and dog,

Fig. 5 is a fragmentary sectional view 55 showing the push rod and controlling spring,

Fig. 6 is a diagrammatic view of the switch applied to a battery, coil and distributor ignition system,

Fig. 7 is a diagrammatic view showing the 60 switch and hook-up for a magneto ignition apparatus, and

Fig. 8 is a diagrammatic view showing the switch and hook-up for a dual ignition apparatus including both magneto and battery, coil and distributor.

Referring now to the drawings in which like characters of reference designate similar parts in the various views, the magnetic ignition switch is shown to comprise a base 10 70 preferably formed of insulating material, such as bakelite or the like, upon which is mounted, near the top thereof, an angle iron bracket 11. An electro-magnet 12 is secured to the underneath face of the bracket by means 75 of a bolt 13 which also secures an angle iron bracket 14 to the bracket 11, which bracket 14 forms a mounting for the hereinafter described push rod and shaft of the ignition switch.

80 A combined armature and dog, best shown in Fig. 4, is pivoted on the base 10 below the electro-magnet and comprises a dog 15 and an armature 16, which latter projects laterally from the dog to extend underneath the core 85 17 of the electro-magnet, as best shown in Fig. 2. The dog is preferably pivoted to the base by means of a bolt 18, and a substantially V-shaped spring 19 is looped over the bolt, one of the terminals of the spring being 90 hooked over the dog, and the other terminal being hooked over an attaching screw 20, as best shown in Fig. 1, to normally hold the dog pressed downwardly to engage the pivoted switch segment, as will now be described.

95 The pivoted switch segment 21 is preferably formed of insulating material, such as bakelite or the like, and is of the general shape shown in Fig. 1. The upper edge of 100

the segment is notched, as shown at 22, to receive the dog 15. The lower end of the segment is keyed or otherwise rigidly secured to a rock shaft 23 which, as shown in Fig. 2, is journaled at one end in a suitable opening in the base 10 and, at the opposite end, projects through a suitable opening in the above-mentioned front angle iron bracket 14. An ignition switch handle 24 is fixed to the projecting end of the rock shaft for manually turning the shaft clockwise. For automatically turning the shaft counter-clockwise, a spiral spring 25 encircles the shaft in front of the segment 21, one end of the spring being rigidly secured to the shaft in any preferred manner, and the opposite end being hooked over a pin 26 carried by the base plate.

The switch points are mounted, as usual, on the pivoted segment 21 and, as best shown in Fig. 2, comprise a pair of arcuate copper or other metal arms 27 and 28 which are riveted or otherwise fixed at the inner ends upon the segment and extend from opposite sides of the segment. The arm 27 is provided with spaced fingers 29 and 30 which are bent obliquely toward the base 10 and terminate in disks 31 and 32 which have wiping contact with corresponding fixed switch contacts 33 and 34 on the base 10 and which are connected, as will be hereinafter more fully described, by corresponding conductor wires 35 and 36 preferably to the ammeter and to the high tension coil.

Likewise, the arm 28 is provided with fingers 37 and 38 which terminate in disks 39 and 40, respectively, which have wiping contact with respective stationary switch contacts 41 and 42, carried by the base 10, when the segment 21 is moved by the controlling spring 25 thereof counter-clockwise to ground the magneto ignition apparatus, the stationary switch contacts 41 and 42 being connected by corresponding conductor wires 43 and 44 to the ground and to the magneto, respectively.

It is now clear that when the pivoted switch segment 21 is manually turned clockwise by means of the ignition switch handle 24, the dog 15 will lodge in the notch 22, as shown in Fig. 1, and hold the segment in this position. For the purpose of manually releasing the dog when necessary, a push rod 45, as best shown in Figs. 2 and 5, is slidably and non-rotatably fitted in openings in the base 10 and front angle iron bracket 14 and is equipped on the upper side with a tooth 46 having an inclined cam surface 47 on the rear edge which, when the push rod 60 is moved inwardly, rides upon the underneath edge of the dog 15 and rocks the dog upwardly against the tension of its controlling spring 19 to dislodge the dog from the notch 22 and permit the spring-pressed pivoted segment 21 being instantly moved in a

counter-clockwise direction by its controlling spiral spring 25.

The purpose of the electro-magnet 12 is to release the dog automatically and, to this end, the electro-magnet coil 48 has one terminal 49 thereof connected to the above-mentioned stationary or fixed switch contact 34 which is in the battery circuit. The other terminal 50 of the coil is connected to a binding post 51 on the base 10 from which a wire 52 leads, as best shown in Figs. 6, 7 and 8, to the oil gage 53 and temperature gage 54.

Each gage is provided with an insulated binding post 55 in the path of movement of the indicating hand 56 which is, of course, grounded. Said wire 52 is connected to said insulated binding posts by corresponding wires 57 and 58.

It will be now clear that in the event of the oil pressure or level dropping dangerously low, for example to two or three pounds, or in the event of the temperature of the cooling system rising dangerously high, a circuit may be traced from the storage battery B, see Fig. 6, through the wire 35, finger 29, arm 27, finger 30, wire 49, coil 48 of the electro-magnet, and through the wire 52 to the grounded hand of the oil or temperature gage, so that the electro-magnet is energized.

The electro-magnet thereupon attracts the armature 16, thereby rocking the dog 15 on its pivot and dislodging it from the notch 22 in the segment 21. The segment is instantly rotated counter-clockwise by its controlling spring 21 to disengage the fingers 29 and 30 from the fixed contacts 33 and 34, which are in series circuit with the battery B and coil 59 through the wire 35 and the wire 36, see Fig. 6, so that the primary ignition circuit is broken by such movement of the pivoted segment 21.

Simultaneously with the opening of the battery circuit, where a dual ignition hook-up including a magneto is also employed, as shown in Fig. 8, the movement of the segment by its spiral controlling spring moves the fingers 37 and 38 into contact with the stationary switch contacts 41 and 42 to ground the magneto, since in such position of the parts a circuit may be traced from the ground terminal of the magneto through the wire 44, stationary contact 42, fingers 38 and 37, stationary contact 41 and ground wire 43.

In the diagrammatic view shown in Fig. 7, the switch as shown employed in connection with magneto ignition only, and, in this connection, it will be observed that the usual ignition storage battery is dispensed with and, in lieu thereof, a small battery, such as the single cell "Hot Shot" battery, marked B', may be connected to the battery terminal 33 for cooperation with the electro-magnet coil which, in this instance, acts in the same man-

ner as above described in detail, as will be understood.

The primary purpose of the push rod 45 is to manually open the ignition circuit whenever desired, and, for this purpose, the push rod is equipped, as will be observed by referring to Fig. 2, with a knob 63 on its outer end. A leaf spring 60, as best shown in Fig. 5, is secured at one end to the back of the base 10 by means of a screw 61 and bears with its free end against the inner end of the push rod, which, as will be observed, projects through an opening in the base plate. The leaf spring thus holds the push rod at its outer limit of movement so that the cam surface 47 will be disposed normally out of engagement with the dog. It is clear, however, that, by simply pushing in on the knob 63, the cam surface will be brought into engagement with the dog, as above described, and the dog will be lifted and dislodged from the notch 22 in the pivoted switch segment 21 to permit the latter being moved by its controlling spring to open the ignition circuit, as above described.

It will be observed that when the ignition switch is initially turned to close the primary ignition circuit, when the motor is cold at starting, the grounded hand of the oil gage will be in engagement with its contact 55, so that the electro-magnet will be energized and will automatically open the ignition circuit. In order to counteract the effect of the electro-magnet when starting, it is, therefore, necessary to manually hold the ignition switch handle 24 stationary so that the ignition circuit from the battery through the coil and distributor will be maintained closed until the motor starts, even though the parallel electric circuit through the gages and through the electro-magnet is grounded at the oil gage.

By referring to Figs. 1 and 3, it will be observed that an additional stationary contact 62 is provided in the path of movement of the finger 34 on the switch arm 27. This switch contact may be grounded when the switch is used in connection with Electro-Lock cable, so that the igniton circuit from the coil and distributor will be grounded through the fingers 29 and 34, being disposed in engagement with the fixed contact 34 and additional fixed contact 32 when the ignition switch segment 21 is in "off" positon, or at its extreme limit of movement in a counter-clockwise direction.

It is thought that, from the above description, the construction and operation of my invention will be thoroughly understood without further explanation.

Having thus described the invention, I claim:

1. The combination with the ignition devices of an internal combustion motor and the cooling and pressure lubrication system thereof, of a magnetic ignition switch includ-

ing a pressure and heat gage controlled electro-magnet, a switch segment operably connected to the electro-magnet armature and electrically connected with the ignition devices, said segment being adapted to be instantly released by the magnet to open the circuit to the ignition devices upon a predetermined drop in oil pressure or predetermined rise in temperature of the cooling system, and means for releasing the segment independently of the magnet. 75

2. The combination with the ignition devices of an internal combustion motor and the cooling and pressure lubrication system thereof, of a magnetic ignition switch including a pressure and heat gage controlled electro-magnet, a spring-pressed switch segment having contact fingers extending from opposite sides thereof, a series of stationary contacts adapted to be electrically connected with said ignition devices, an armature for the electro-magnet having a dog engaging said segment for holding the segment in on position, energizing of said electro-magnet by a predetermined drop in oil pressure or a predetermined rise in temperature actuating said magnet to dislodge said dog and release said segment to be moved by its controlling spring to off position to open the ignition circuit to said devices, and a manually operable push rod having a cam surface adapted to engage said dog and release the same from the segment independently of said magnet. 90

3. An electro-magnetic ignition switch for internal combustion motors including stationary switch contacts adapted to be connected in series with the primary ignition circuit of the ignition devices of the motor, an electro-magnet adapted to be connected in series with an insulated contact in the path of a grounded hand of an oil pressure gage of the motor and with one of said stationary contacts, a pivoted spring-controlled switch segment having a plurality of switch contacts adapted to engage with the stationary contacts and close the circuit to said ignition devices, a pivoted spring-pressed dog engaging said segment for normally holding the segment in on position, an armature carried by the dog and extending laterally therefrom over the core of said magnet and adapted to be attracted when the magnet is energized by the oil gage hand impinging against said insulated contact and dislodging the dog from the segment to permit the segment to be moved to off position by its controlling spring to disengage the segment contacts from the stationary contacts and open the ignition circuit, and a manually operable push rod between the segment and dog adapted to dislodge the dog from the segment independently of the armature. 110

4. An electro-magnetic ignition switch for internal combustion motors including stationary switch contacts adapted to be con- 130

nnected in series with the primary ignition circuit of the ignition devices of the motor, an electro-magnet adapted to be connected in series with an insulated contact in the path of
5 a ground hand of a heat gage of the motor cooling system and with one of said stationary contacts, a pivoted spring-controlled switch segment having a plurality of switch contacts adapted to engage with and electrically connect the stationary contacts and close the circuit to said ignition devices, a pivoted spring-pressed dog engaging in a notch in said segment for normally holding the segment in on position, an armature integral with the dog
10 and extending laterally therefrom over the core of said magnet and adapted to be attracted when the magnet is energized by the heat gage hand impinging against said insulated contact and dislodging the dog from the segment to permit the segment to be moved to off position by its controlling spring to disengage the segment contacts from the stationary contacts and open the ignition circuit, and a manually operable push rod between the segment and dog adapted to dislodge the dog from the segment independently of the armature.

5. In a dual ignition system for internal combustion motors, a magneto and battery ignition devices, a series of fixed switch contacts adapted to be electrically connected in circuit with said magneto and devices, a switch segment having switch contacts adapted to engage with and electrically connect certain of said fixed contacts, a pivoted dog adapted to engage the segment and hold the segment in on position, an armature carried by the dog, an electro-magnet adapted to be connected in series with one of said stationary contacts and with an insulated contact in the path of movement of a grounded hand of a controlling gage of the motor, energizing of said magnet by contact of said hand with said insulated contact attracting the armature and dislodging the dog from the segment, a spring for returning the segment to off position upon disengagement of the dog to open said ignition circuit and ground the magneto, and means for releasing the dog independently of the armature.

In testimony whereof I affix my signature.
WILLIAM E. ALBERTSON.
